UNITED STATES PATENT OFFICE

HARRY C. BOARDMAN, OF CHICAGO, ILLINOIS, ASSIGNEE TO CHICAGO BRIDGE & IRON COMPANY, OF CHICAGO, ILLINOIS, A CORPORATION OF ILLINOIS

TANK

Application filed January 10, 1931. Serial No. 507,985.

This invention relates to improvements in tanks and, more especially, tanks with suspended bottoms. The invention is particularly applicable to elevated steel tanks with 5 curved suspended sheet metal bottoms.

Cylindrical elevated tanks are in general use. When such tanks are provided with flat bottoms, considerable bracing and supporting means are required. It has been customary, therefore, to provide such tanks with 10 suspended curved sheet metal bottoms supported at the edges. Such bottoms have been made hemi-spherical and hemi-ellipsoidal in shape. In the latter case, an additional support has frequently been provided at the 15 center by a riser pipe, or otherwise.

The principal feature of my invention is the provision of a bottom for the kind of tank described, so curved that it will be substantially equally stressed throughout its 20 area. This will permit the use of metal of substantially uniform thickness in a bottom of this kind which is suspended by its edge or edges. Obviously, when the tank is full 25 of liquid, the pressures on points in the bottom at different heights will be different because of the different heads of liquid and tensional stresses due to the support of the bottom by the edge or edges. Owing to the 30 particular curvature employed, however, the maximum stresses at all points in the bottom will be substantially uniform.

Other features and advantages of my invention will appear more fully as I proceed 35 with my specification.

In those forms of devices embodying the features of my invention shown in the accompanying drawings—

Figure 1 is a view partly in side elevation and partly in section of an elevated tank with a suspended bottom supported only at its outer edge; Fig. 2 is a diagrammatic view showing the method of obtaining the curvature of the bottom; Fig. 3 is a view similar 45 to Fig. 1, showing a bottom suspended at

its outer edge and also at its inner edge by the provision of a centrally arranged riser pipe; Fig. 4 is a diagrammatic view showing the method of obtaining the curvature of the bottom of the tank of Fig. 3; and 50 Fig. 5 is a view similar to Fig. 4, showing a modification.

The tank shown in Fig. 1 has a cylindrical body portion 10 supported on posts 11. The bottom 12 is preferably made of sheet metal 55 and so curved that the maximum stresses at all points are substantially uniform. This permits the use of metal of substantially uniform thickness, thus making for economy 60 and simplicity in cost and manufacture. 65

I shall now describe in detail the method of determining the curvature of the bottom 12 to achieve the objects of the invention as above set forth. It will be seen that the tank is a solid of revolution about a vertical central axis and that all diametrical sections of the bottom are similar. It will be necessary, therefore, to obtain only the curvature of 70 such a section.

Fig. 2 represents the curve of a diametrical section of the bottom 12. This curve is obtained as follows. CL represents the center line of the tank. B is the low point on the bottom. C is the maximum height of water. r_1 represents the radius of curvature in a 75 plane perpendicular to the drawing or paper through a line normal to the surface of the bottom. r_2 represents the radius of curvature in the plane of the drawing or paper through a line normal to the surface of the bottom. T 80 represents the tension or stress and P the pressure.

For the purpose of illustration, I shall show the method applied to a water tank with a diameter of substantially 40 feet and a total height of substantially 40 feet from the low point in the bottom to the upper edge of the cylindrical body portion or shell. That is 85 the distance BC is 40 feet. In the practice of the invention, it may be necessary to resort

to experimentation or the trial and error method to determine the curve and thickness of metal for tanks of certain desired capacities and dimensions. In the case given, it will be assumed that the permissible tension in the bottom plates is 31,500 pounds per linear foot. This may have been obtained, for example, on the assumption that $\frac{3}{8}$ sheets will be used, designed for a stress of 10,000 pounds per square inch. In order to obtain a factor of safety, or allowing for weakness in joints, the plates may be rated at 70%. This makes the permissible stress $10,000 \times \frac{3}{8} \times .70$, which equals 2,620 pounds per linear inch or 31,500 pounds per linear foot. It will be seen hereinafter, however, that all that is necessary is to know the permissible stress. The curvature can then be ascertained. The permissible stress in any material to be used may be computed in any desired manner.

Assuming, in the case given, that T equals 31,500 and that the tank is 40 feet high, r_1 and r_2 can be found at all points in the following manner. Commencing at B, it is known that a 40 foot head of water will exert a pressure of approximately 40×62.5 pounds or 2500 pounds. It is also known that at any point on the bottom

$$30 \quad r_2 = \frac{T}{P - \frac{T}{r_1}}$$

35 This is obtained from the equation

$$T = \frac{P}{\frac{1}{r_1} + \frac{1}{r_2}}$$

40 which is an accepted engineering formula or equation in matters of this kind. The transposition of these equations is as follows:

$$45 \quad T = \frac{P}{\frac{1}{r_1} + \frac{1}{r_2}}$$

$$T = \frac{P}{\frac{r_1 + r_2}{r_1 r_2}}$$

$$T = \frac{P r_1 r_2}{r_1 + r_2}$$

$$55 \quad Tr_1 + Tr_2 = Pr_1 r_2$$

$$Pr_1 r_2 - Tr_2 = Tr_1$$

$$r_2(Pr_1 - T) = Tr_1$$

$$60 \quad r_2 = \frac{Tr_1}{Pr_1 - T}$$

$$r_2 = \frac{T}{P - \frac{T}{r_1}}$$

65

At B, r_1 and r_2 are equal. Using the equation given:

$$r_2 = \frac{T}{P - \frac{T}{r_2}}$$

$$r_2 = \frac{T}{Pr_2 - T}$$

$$r_2 = \frac{Tr_2}{Pr_2 - T}$$

$$1 = \frac{T}{Pr_2 - T}$$

$$Pr_2 - T = T$$

$$Pr_2 = 2T$$

$$r_2 = \frac{2T}{P}$$

Using the assumed data, r_2 at B is obtained as follows:

$$r_2 = \frac{2 \times 31,500}{2500} = 25.2 \text{ feet}$$

It will be seen that if the assumed tension is smaller, r_2 will be shorter. If the assumed permissible tension is too small, r_2 will be so short that the bottom curve, if plotted as hereinafter described, will not reach the side of the body cylindrical portion. Consequently, the permissible tension must be great enough so that r_2 will be long enough at B so that the curve when plotted, will connect with the cylindrical body portion of the tank. The greater the assumed tension, the longer r_2 will be and the flatter the bottom will be. With lesser assumed tensions, the bottom will be more curved. As stated, however, the curve must be flat enough so that the bottom will join the sides of a cylindrical body portion of the diameter desired.

This distance may then be measured vertically on the line CL, giving the center D, the distance D-B being 25.2 feet. With the center D and radius DB, the arc BE is then drawn. At E, the pressure will be less than at B because of the reduced head. This head at E may be measured vertically from E to the maximum water line CW. Assuming this distance to measure 38.4 feet, P at E will be 2400. It will be seen, therefore, that r_2 , as taken for B, will not be correct at E. The correct r_2 , however, at E can be obtained by using the equation:

$$r_2 = \frac{T}{P - \frac{T}{r_1}}$$

In a solid revolution r_1 will always be the distance from the point in question along r_2

from the point to where r_2 intersects the center line CL. At E, therefore:

$$r_2 = \frac{31,500}{2400 - \frac{31500}{25.2}} = 27.4 \text{ feet.}$$

A new center may then be formed by extending the line E D to F, the distance E F being 27.4, which is the new r_2 .

With this new radius 27.4 and using the center F, another arc E G is drawn and a new r_2 obtained at this point. At G, r_1 is the distance along G F from G to the point where G F intersects the line C L at H. The distance G H can be measured and it will be assumed that this distance is 26 feet. This gives r_1 at G as 26 feet. The head at G can also be measured and the pressure obtained. Assuming that the vertical distance from G to the line C W measures 36 feet, P at G will be 2250. A new and correct r_2 at G can then be formed as follows:

$$\text{At } G, r_2 = \frac{31500}{2250 - \frac{31500}{26}} = 30.3 \text{ feet.}$$

Measuring 30.3 from G along the line G H extended gives J as the new center for the correct r_2 at G.

With the new center J, the arc G K can be drawn. r_1 at K will be the distance K M. Assume that this measures 26.5. Assuming the head at K to measure 33.6 feet, P at K will be 2100. A new r_2 at K can then be ascertained as follows:

$$\text{At } K, r_2 = \frac{31,500}{2100 - \frac{31500}{26.5}} = 34.6.$$

The new r_2 or 34.6, can then be measured along the line K M extended to the point N. K N is then the new r_2 at K and with this radius, the arc K P is drawn with N as a center. In this manner, the curve is continued until the side W P of the tank is reached. As here shown, the diameter W R is taken as 40 feet. Obviously, any desired diameter may be taken and the curve continued until the side is reached. By taking more and shorter arcs, greater accuracy is obtained.

In Figs. 3 and 4, I have shown a bottom suspended by its outer edge, which is attached to the cylindrical body portion and also by its inner edge which is attached to the upper edge of the central riser pipe S which acts as a support. The curve for this bottom is shown in Fig. 4 and the method of producing it is substantially the same as above described.

As here shown, C L represents the center line of the tank. In this case, the diameter W R is taken as 80 feet. B' is the lowest point in the bottom and corresponds to B in Fig. 2. It is assumed that 3/8" metal is used as above described and that the permissible ten-

sion or stress 31,500 pounds, as computed above. The desired diameter of the riser pipe is also taken arbitrarily and here this is assumed to be S T. The maximum desired water depth is also arbitrarily taken and this is assumed to be 50 feet, which is the vertical distance from the line X Y to the line W R.

The point B' is arbitrarily chosen somewhere on the line X Y, preferably about midway between X and Y, or somewhat nearer Y. By trial or experiment, the permissible tension must be great enough so that the radii (r_2) will be long enough so that the curve will be flat enough to reach the side wall W V and the riser at S at the desired heights. If the r_2 radii are too short, the bottom curve will not connect with the shell or riser or will connect at points which are higher than desired. By increasing the permissible tension, however, the bottom may be made as flat as desired.

Assuming the point B' in Fig. 4 to be located as above described, the curve from B to V is made substantially as described in connection with Fig. 2. That is, as follows. The permissible tension is 31,500. The pressure at B is 50 x 62.5 or 3125. r_1 at B is infinity. Therefore, by the equation given above:

$$\text{At } B, r_2 = \frac{31500}{3125 - \frac{31500}{\infty}} = 10 \text{ feet.}$$

With the radius r_2 as 10 and D' as a center, the arc B E' is drawn. At E', the height can be measured from E' to the line W R. Assuming this to measure 48 feet, the pressure at E' is 3000 pounds. A new and correct r_2 can then be ascertained for E'. At E', r_1 is the distance from E' along the line E' D' extended until it intersects C L at H'. Assume this to be 50 feet. Therefore,

$$\text{At } E', r_2 = \frac{31500}{3000 - \frac{31500}{50}} = 13.8 \text{ feet.}$$

A new center is then found by extending the line E' D' to F', the distance E' F' being 13.8 feet.

With this new radius 13.8 feet and using the center F', another arc E' G' is drawn and a new r_2 similarly obtained at this point. At G', r_1 is the distance along G' F' extended to where it intersects C L at M'. Assume this to measure 45 feet. Assume the head of water at G' to measure 44.8 feet, the pressure at G' will be 2800. Therefore,

$$\text{At } G', r_2 = \frac{31500}{2800 - \frac{31500}{45}} = 15 \text{ feet.}$$

A new center is obtained by measuring 15 feet from G' along the line G' F' extended to

J'. With the center J', the arc G' K' is drawn. At K', r_1 will be the distance K' N'. Assume the water head to measure about 38.2 feet at K', the pressure will be 2390 pounds. 5 Assume K' N' to measure 40.2 feet. Therefore,

$$At K', r_2 = \frac{31500}{2390 - \frac{31500}{40.2}} = 19.6 \text{ feet.}$$

10

Measuring this along the line K' J' from K' gives the new center at N''. With this new center, the arc K' V is drawn. This brings the curve into the side of the cylindrical body portion.

15 The curve B S is obtained in a similar manner, except that r_1 becomes minus so that

$$20 \quad r_2 = \frac{T}{P - \frac{(-T)}{r_1}} \quad \text{or} \quad r_2 = \frac{T}{P + \frac{T}{r_1}}$$

With the center D', the arc B' E'' is drawn. At this point, r_1 is the line E'' H'', which is the extension of the line D' E'' to where it intersects C L at H''. Assume that this measures 43 feet and that the pressure at E'' is 25 3000 pounds.

$$30 \quad At E'', r_2 = \frac{31500}{3000 + \frac{31500}{43}} = 8.4 \text{ feet.}$$

Measuring 8.4 feet from E'' gives the new center F''. Using this, the arc E'' G'' is 25 drawn.

25 r_1 at G'' is the distance G'' M''. Assume this to measure 26 feet.

$$40 \quad r_2 \text{ at } G'' = \frac{31500}{2800 + \frac{31500}{26}} = 7.9 \text{ feet.}$$

Measuring 7.9 feet from G'' gives the new center J'' and using this, the arc G'' S is drawn which brings the bottom into the riser 45 pipe.

In the case where a bottom is supported at both its inner and outer edges, as shown in Figs. 3, 4 and 5, the curve may be plotted by commencing at V with the curve tangent 50 to the line W V. This is shown in Fig. 5. This requires that the center for the first r_2 be taken on the horizontal line V V'. In such case r_1 at V will be the radius of the tank which is assumed to be 40 feet. Assume 55 that it is desired that the cylindrical body portion be 30 feet high so that the water head at V will be 30 feet.

$$60 \quad \text{Then at } V, r_2 = \frac{31500}{1875 - \frac{31500}{40}} = 29 \text{ feet.}$$

65 The radius 29 feet is then used with the center 100 to draw the arc V K''. At K'', a new r_2 may be computed as follows. At K'', r_1 equals the distance K'' N'''. Assume the

pressure at K'' to measure 2390 pounds. Assume K'' N''' to measure 40.2.

$$At K'', r_2 = \frac{31500}{2390 - \frac{31500}{40.2}} = 19.6 \text{ feet.}$$

70

Measuring the distance 19.6 feet from K'' gives the new center 101. With this center, the arc K'' 102 is drawn. r_1 at 102 is 75 102-103, which measures 45 feet. Assume the pressure at 102 to be 2800 pounds.

$$At 102, r_2 = \frac{31500}{2800 - \frac{31500}{45}} = 15 \text{ feet.}$$

80

Measuring 15 feet from 102 gives the new center 103 and the arc 102-104 is drawn. At 104, r_1 is the distance 104-105 which measures 60.5. Assume the pressure at 104 to be 85 3000.

$$At 104, r_2 = \frac{31500}{3000 - \frac{31500}{60.5}} = 12.7 \text{ feet.}$$

90

This gives the new center 105 and the arc 104-106 is drawn until the radius becomes vertical which must be the lowest point of the bottom. At the point 106, r_1 is infinity. Assume the pressure to measure 3125 pounds at 95 106.

$$At 106, r_2 = \frac{31500}{3120 - \frac{31500}{\text{infinity}}} = 10 \text{ feet.}$$

100

Measuring 10 feet vertically from 106 gives the new center 107.

The curve is similarly continued to the right of the vertical line through 106, except that in compiling r_2 , it is to be noted that r_1 becomes minus. r_2 , therefore, equals

$$\frac{T}{P - \frac{(-T)}{r_1}} \text{ or } r_2 = \frac{T}{P + \frac{T}{r_1}}$$

110

With the radius 10, the arc 106-108 is drawn. At 108, r_1 is the distance 108-109. Assume this measures 43 and that the pressure at 108 is 3000.

115

$$At 108, r_2 = \frac{31500}{3000 + \frac{31500}{43}} = 8.4 \text{ feet.}$$

Using the distance 8.4 feet, the center 110 is 120 obtained for the new r_2 at 108 and the arc 108-111 drawn.

If the pressure at 111 is 2800 and the distance 111-112 measures 26, then

$$125 \quad r_2 \text{ at } 111 = \frac{31500}{2800 + \frac{31500}{26}} = 7.9 \text{ feet.}$$

This distance gives the new center 113 and the arc 113-114 is drawn. It will be seen that 130

at 114, the arc becomes vertical and, therefore, the curve must be stopped there and the riser pipe 115 made of sufficient diameter to support the inner edge of the bottom at 6 that point.

Evidently if a thicker bottom plate is used with a greater permissible tension (larger T), the curve will be flatter and will come in further toward the center so that the diameter of 10 the riser pipe may be smaller.

It is also obvious that in making the curve, the inner end need not be carried inwardly so that it becomes vertical and joins the riser pipe on a tangent, but it may be stopped at 15 any point desired and the riser pipe attached.

In the curve shown in Fig. 4, the data taken were similar to those used in Fig. 5 and, consequently, the curve at V and S comes into the shell and riser, respectively, substantially 20 on a tangent. Obviously, however, in this case, if heavier bottom plates were used with a greater value of T, the curve would be flatter and the bottom would come into the shell at V not on a tangent, but more as the bottom 25 joins the shell at P in Fig. 2. Likewise, the curve would not meet the riser pipe at S as a tangent, but at a larger angle.

While I have shown and described certain 30 embodiments of my invention, it is to be understood that it is capable of many modifications. Changes, therefore, in the construction and arrangement may be made without departing from the spirit and scope of my invention as disclosed in the appended claims, 35 in which it is my intention to claim all novelty inherent in my invention as broadly as permissible, in view of the prior art.

What I regard as new, and desire to secure by Letters Patent, is:

40 1. A tank of the character described with a substantially cylindrical body portion having a curved sheet metal bottom with a central opening, said bottom being suspended partly by its outer edge and partly by its 45 inner edge surrounding said opening, said bottom being so shaped that a diametrical vertical section defines two similar curves in each of which the successive radii from the lowest bottom point to the outer edge are 50 successively longer and from the lowest point to the inner edge are successively shorter.

2. A tank of the character described with a substantially cylindrical body portion having a curved sheet metal bottom with a central opening, said bottom being suspended partly by its outer edge and partly by its inner edge surrounding said opening, said bottom being so shaped that a diametrical vertical section defines two similar curves in 55 each of which the successive radii from the lowest bottom point to the outer edge are successively longer and from the lowest point to the inner edge are successively shorter and in which such radius at each point is shorter 60 than the radius in a plane at right angles to

the plane of the section and passing through a line normal to the surface at such point.

3. A tank of the character described with a substantially cylindrical body portion having a curved sheet metal bottom with a central opening, said bottom being suspended partly by its outer edge and partly by its inner edge surrounding said opening, said bottom being so shaped that a diametrical vertical section defines two similar curves in each of which the radius at each point is shorter than the radius in a plane at right angles to the plane of the section and passing through a line normal to the surface at such point.

In witness whereof, I have hereunto set my hand and seal, this third day of January, 1931.

HARRY C. BOARDMAN.
